CASKET HANDLE BRACKET

Herman E. Moore, % Parsons Casket Hardware
Company, Belvidere, Ill.

Filed Aug. 20, 1962, Ser. No. 71,352

Term of patent 14 years

(Cl. D19—2)

FIGURE 1 is a side elevational view of a casket handle bracket embodying my new design.

FIG. 2 is a plan view thereof.

FIG. 3 is an end elevational view.

FIG. 4 is a sectional view taken along the line 4-4 of FIG. 2.

FIG. 5 is a fragmentary sectional view taken along the line 5-5 of FIG. 1.

FIG. 6 is a fragmentary sectional view taken along the line 6-6 of FIG. 4.

I claim:

The ornamental design for a casket handle bracket, substantially as shown.
